COMBINATION STORM WINDOW, SCREEN AND AWNING

Abraham Hurowitz, Brookline, and Wilbur S. R. O'Neill, Chelmsford, Mass., assignors to Morrell Aluminum Products, Inc., Garfield, N.J.

Application August 29, 1957, Serial No. 680,989

3 Claims. (Cl. 160—91)

Our invention relates generally to combination storm windows and screens and specifically to storm windows and screens having an awning section adapted to receive translucent or opaque shade panels.

It is among the objects of our invention to provide a combination storm window having an awning section which performs the dual function of serving as an awning and also cooperatively forms a portion of the storm window.

It is a further object of our invention to provide a combination storm window having an adjustable awning section.

Yet a further object of our invention is to provide a combination storm window, having both screen and awning sections for ordinary summer use as well as storm window sections for winter use.

A still further object of our invention is to provide a combination storm window, having an awning section which will receive any one of a plurality of inserts of varying colors and of varying degrees of translucence or opacity.

A further object of our invention is to provide a combination storm window which is relatively simple in form, inexpensive, easy to maintain, durable, and easy to install.

These objects and advantages, as well as other objects and advantages, may be achieved by the device presented by way of illustration in the drawings in which

Figure 1 is a side elevational, cross sectional view, showing our combination storm window with the awning section extended and with the panel insert in position in the awning section.

Figure 2 is a similar view with the panel omitted from the awning window and the awning window shown in dotted lines, in a partially retracted position.

Figure 3 is a side, elevational, sectional view, showing the awning window engaged with the frame and the screen raised and the glazed window sash lowered in position for winter use as a storm window.

Figure 4 is a cross-sectional view, taken on the lines 4—4 in Figure 1, looking in the direction of the arrows.

Figure 5 is a partial view in perspective, showing the awning window latch and a portion of the shade panel.

Figure 6 is a view of the edge of the shade panel.

Referring now to the drawings in detail, our storm window is provided with a rectangular frame 11. The frame 11 is provided with a header 12 at the top, disposed horizontally and a bottom 13, likewise disposed horizontally. The header 12 and the bottom 13 are connected together by side rails 14, 14. The side rails 14, 14 are provided with pairs of tracks 15 in which sashes may slide, these tracks 15 are arranged in opposition to each other. In the inner track 15, a slideable screen sash 16 is positioned. In Figures 1 and 2, the screen is in lower position such as would be desirable for normal summer operation. In the outer track 15, of the two tracks in the side rails 14, a sliding, glazed,

2

window sash 17 is positioned. In Figures 1 and 2 this sash 17, which normally functions as one section of a storm window, is raised out of the way for normal summer operation. This sliding, glazed, window sash 17, in cooperation with the normal, double-hung window sashes of a window opening, forms a dead air space which helps to insulate the interior of the dwelling from the heat of the rays of the sun. At the top of the header 12, by means of the hinge 18, an awning window 19 is pivotally secured. This awning window is substantially rectangular in form and has a top rail 20 and a bottom rail 21. These are connected together by side rails 22, 22. The rectangular frame or awning window 19, defined by these rails 20, 21 and 22, 22, has a pair of ears 15 or enlargements 23, formed near its lower edge. Likewise, on the outer face of the side rails 14, 14, corresponding ears 24 are attached. A two-piece, jackknife brace 25 is pivotally secured at either end to the enlargements 23 and 24. The jackknife brace 25 is formed in two sections 26, 27, which are pivotally secured together at their center point by a pin 28. A pair of these jackknife braces 25, 25 will be secured to both sides of the awning window 19 and both sides of the frame 11. The jackknife braces 25, 25 are provided with detents 29, so that they may not jackknife below the straight position shown in Figure 1, but only upwardly as shown by the dotted lines in Figure 2. The detent 29 seats itself in the slot 30.

In the bottom, horizontal edge of the awning window 19, a slotted channel 31 is formed. A loop 32 extends from the slot. The ends of the loop 32 lie in this channel. One end carries a spring 33 which normally urges the opposite end 34 out of the channel. The side rails 14 carry a lug 35, having an aperture 36 to receive the end 34 of the loop 32. This constitutes the latch 37, by which the awning window 19 is held firmly engaged in the position shown in Figure 3, during winter use, when it is not functioning as an awning, but functioning cooperatively with the window sash 17 to form a storm window. The awning window 19 is provided with the usual transparent glass insert 38, and the usual cushion strip 39.

In the outer face of the awning window 19, opposite lateral channels 40, are formed by L-shaped extensions 41. A shade panel 42, slideable in the channels, 40, 40, is positioned therein for summer use. This shade panel may be opaque or translucent. It may be colored to fit the color scheme of the building to which the combination window is applied. As the color of the structure may change upon repainting, this shade panel 42 may be discarded and a matching color shade panel may be substituted. The top edge of the shade panel is provided with a binder or bumper strip 43. The side edges 44, 44 engage the channels 40, frictionally to maintain the shade panel in place. The bottom edge 45 is provided with a longitudinal pull-tab 45, so that the tab 45 can be grasped and the panel conveniently inserted or withdrawn.

In order to limit the degree of insertion of the shade panel 42, the top of the awning window 19 has a transverse, L-shaped extension 46, against which the strip 43 abuts.

The awning window 19 has inwardly disposed flanges 47 opposite the outer face of the combination window 11. These flanges 47 are provided with sealing gaskets 48, so that when the awning window 19 is lowered to the position shown in Figure 3, it will firmly seat and engage awning window 19 with the frame 11 and form a weather-proof seal.

In Figures 1 and 2, we have shown the hinge 18 in the form of a pair of interlaced arcuate flanges. It is to be

understood that this hinging construction is merely a matter of choice and that other types of hinging or pivotal attachments may be substituted, as many are well-known in the trade.

The use of our combination window is as follows:

For winter use, the screen 16 is raised as shown in Fig. 3 and the storm window sash 17 is lowered as shown in Fig. 3. The awning window 19 is lowered to the position shown in Fig. 3 and firmly latched. Cooperatively, the glasses 17 and 38 form a complete storm window coverage for the double-hung windows normally used in window openings.

For summer use, the awning 19 is raised as shown in Figures 1 and 2. The awning panel of choice is inserted in the panels 40, and this panel 42 provides the desired awning shade. The glazed sliding window sash 17 is raised to the position shown in Figures 1 and 2 and the screen sash 16 is lowered to the position shown in Figures 1 and 2. It will thereby be seen that the awning window 19 performs the dual function of serving as an awning in the summer and a storm window in the winter, without the necessity for a triple-track as is usually required in combination screen and storm windows. Thereby, our combination storm window, screen and awning provides a window which is relatively small in width, conserves material, may therefore be manufactured more cheaply and is lighter in weight and easier to install than triple-track windows.

The materials of which our combination storm window, screen and awning are made are preferably the usual aluminum extrusions, by which top and bottom rails and side rails are attached together by screws or corner keys in any conventional chosen manner. The awning window, likewise, may be formed of four extruded aluminum strips. The screen sash may be provided with metal or plastic screening and the sash itself may be the usual aluminum extrusion, i. e., four extruded aluminum strips attached together at the corners. The glazed sash likewise may be formed of four extruded aluminum strips attached together with the usual glass insert. The awning window 19 may be formed of four extruded aluminum strips and have an appropriate glass panel 38. The shade panel is preferably a plastic panel and may be provided in color. Such a panel, if translucent, could be colored to match the color of the building to which the combination window is applied, or the color could be chosen with a view to casting a particular type of colored light into the room to which the storm window is applied. Also, instead of a translucent panel, an opaque panel of plastic or metal may be supplied so as to give complete shade.

While extruded aluminum is relatively inexpensive and readily available for combination window constructions, other materials such as plastic or wood may be equally satisfactory.

The foregoing description is merely intended to illustrate an embodiment of the invention. The component parts have been shown and described. They each may

have substitutes which may perform a substantially similar function; such substitutes may be known as proper substitutes for the said components and may have actually been known or invented before the present invention; these substitutes are contemplated as being within the scope of the appended claims, although they are not specifically catalogued herein.

We claim:

1. A combination storm window, screen and awning comprising a frame in conformity with a window opening, opposed vertical outer and inner tracks in the frame, a sliding screened sash positioned for vertical movement in the inner tracks, a sliding glazed sash positioned for vertical movement in the outer track, an awning window hingedly secured to the outside of the frame at the top thereof, a support attached to the awning window and the frame, a releasable catch means for securing the awning window in close engagement with the outside of the frame and the top of the lowered sliding glazed sash, and opposed channels in the awning window, a shade panel frictionally engageable with and positioned between the opposed channels.

2. A combination storm window, screen and awning comprising a double-tracked frame, a sliding screened sash positioned for vertical movement in the inner track, a sliding glazed sash positioned for vertical movement in the outer track of the frame, a glazed awning window pivotally secured to the outside of the frame at the top thereof; the glazed awning window closing the upper portion of the frame when pivoted to vertical position and then having its inner lower edge in engagement with the outer top edge of the sliding glazed sash when that sash is in lowered position, a jackknifing support for the awning window pivotally secured at either end to the frame and the awning window respectively, a releasable catch-means for securing the awning window in vertical position in close engagement with the outside of the frame and the lowered sliding glazed sash, opposed channels in the awning window, a shade panel frictionally engageable between the opposed channels.

3. A combination storm window, screen and awning comprising, a frame, a glazed outer sash slidably positioned for vertical movement in the frame, an awning window pivotally secured to the top of the frame, the glazed sash and the awning window cooperatively positionable respectively to completely close the bottom and top of the frame, a screened sash positioned for vertical movement in the frame, and means for supporting the awning window pivoted to a generally outward and downward position, opposed channels in the awning window, a shade panel frictionally engageable in the opposed channels.
